SPEED REGULATING APPARATUS FOR
FLUID DRIVEN PRIME MOVERSCoartland Howland Langworthy, Irwin, Pa., as
signor to Elliott Company, Jeannette, Pa., a
corporation of Pennsylvania

Application August 9, 1950, Serial No. 178,415

1 Claim. (Cl. 137—47)

1.

This invention relates to apparatus for regulating the speed of fluid driven prime movers, and more particularly to such apparatus in which a governor-controlled valve can be closed independently of the governor.

In certain operations it is necessary to operate a prime mover intermittently; for example when a steam turbine drives a blower whose discharge is used only at intervals. In such cases it is preferred to reduce the speed of the blower to a point where it will deliver very little gas, but where it will remain running and be ready to be brought quickly up to normal operating speed. In the past this generally has been done by operating a shut-off valve which is alternately wide open and fully closed. When closed, a small amount of steam is by-passed around the valve to idling nozzles with which the steam turbine is equipped, so that the turbine will keep running. A major disadvantage in such a system is the necessity for introducing a separate control valve to control the speed of the turbine while the shut-off valve is open.

It is among the objects of this invention to provide speed control apparatus for fluid driven prime movers, which does not require an independent shut-off valve, which operates smoothly, which does not require frequent servicing, and which is always ready to bring the speed of the turbine quickly up to its proper operating range. Another object is to provide such apparatus in which a speed control valve also serves as a shut-off valve.

In accordance with this invention a governor valve is mounted in the fluid supply line of a prime mover that is driven by fluid pressure. The valve includes a movable member for controlling fluid flow through it. This member is moved by an axially movable stem projecting from the housing. Mounted adjacent the outer end of the stem is a rod which is movable axially by means actuated in accordance with the speed of the prime mover. The rod is operatively connected to the stem in such a way that movement of the rod in one of its two directions of movement will close the valve. A spring is provided for opening the valve. Selectively operable means are provided for moving the stem against the resistance of the spring to close the valve independently of the position of the rod.

The preferred embodiment of the invention is illustrated in the accompanying drawings in which Fig. 1 is a vertical section through the apparatus with the valve about half way open; Fig. 2 is a side view, partly in section, with the valve closed; and Fig. 3 is a fragmentary end view of the apparatus shown in Fig. 1.

2.

Referring to the drawings, a governor valve housing 1 is provided with an inlet 2 in its side and with an outlet 3 at one end. This valve housing can be connected in a fluid pressure line, such as the line that supplies steam to a turbine (not shown) that may drive a blower or other piece of equipment which is used intermittently but which is kept in continuous operation. Inside the valve housing its inlet is separated from its outlet by a sleeve 4 coaxial with the outlet. This sleeve is provided interiorly with a pair of spaced annular ribs 5 and 7 that form valve seats. Between these ribs the sleeve is provided with a series of circumferentially spaced steam ports 8. The end of the sleeve next to the valve outlet is provided with radial spokes 9, the inner ends of which are joined together to form a bearing 11 in which one end of a horizontal valve stem 12 is slidably mounted. The opposite end of the stem extends slidably through a packing gland 13, with which the end of the valve housing is provided. Inside the valve sleeve a valve member 14 is rigidly mounted on the valve stem for movement with it. This member is formed for engagement with both valve seats simultaneously. The valve member is hollow so that when it is pulled away from the seats some of the steam can flow past the inner seat 7 and then out through the valve member to the valve outlet. When the valve is closed, steam is delivered to the idling nozzles of the turbine through an idling connection 15 communicating with the space between the valve housing and sleeve 4.

The inner end of the valve supports a bracket 17 on which a fluid pressure actuated control 18 is mounted. This control includes a diaphragm 19 that supports a control stem or rod 20 which extends slidably through the top of the bracket. The diaphragm is flexed by liquid pressure under the control of a conventional governor on the turbine. As the speed of the turbine increases, the diaphragm is pressed down, and it is pressed upward when the turbine speed diminishes. Slidably mounted on the control rod below the top of bracket 17 is a block 22 which is provided with a pair of pins 23 that project in opposite directions into the upper fork of a bell crank 24 which is supported by a pivot 25 from the bracket. The lower end of the crank also is forked and straddles a pin 27 pivotally mounted in the opposite sides of a yoke 28 supported by the outer end of the valve stem.

It will be seen that if the upper end of the crank is swung up or down the lower end of the crank will move the valve stem out or in and open or close the valve. The upper end of the

crank is swung down by a pair of jam nuts 30 mounted on rod 29 and engaging the top of the sliding block which as shown in Figs. 1 and 3, normally is held up against these nuts by a coil spring 31 compressed between the bottom of the block and lock nuts 32 on the lower end of the rod. Consequently, when the control rod is moved downward by diaphragm 19 the jam nuts 30 swing the crank in a clockwise direction to close the valve. When the rod is moved upward by the diaphragm, the coil spring 31 swings the crank in the opposite direction to open the valve. The opening and closing of the valve therefore are under the control of the diaphragm which, in turn, is responsive to the speed of the prime mover in a well-known manner. In this way the prime mover can be operated at a constant speed.

When it is desired to slow down the turbine to idling speed the valve is closed by a separate mechanism which is operated at will by an operator or automatically. Although control rod 20 will be in a position to hold the valve open, it will not interfere with closing of the valve because block 22, which will be moved downward by crank 24, can slide down the rod and compress spring 31 as shown in Fig. 2. At the same time the rod will be moved upward, because the reduction in speed of the turbine will cause its governor to call for wider opening of the valve. Of course, this upward movement of the rod at this time can do nothing except compress the spring still more.

The mechanism by which the valve is closed independently of the position of the control rod consists of a crank 35 that can be swung back and forth by a fluid pressure motor. The crank is pivotally mounted in the outer end of a bracket 36 supported by a plate 37 that extends downward from the valve. The motor includes a cylinder 38 oscillatably mounted in the bracket, and a piston rod 39 that projects from the upper end of the cylinder and is pivotally connected to the inner end of the crank. Ordinarily fluid pressure is delivered to the lower end of the cylinder so that the free end of the crank will be swung outward away from the valve as shown in Fig. 1. When it is desired to close the valve independently of the control rod, fluid pressure is delivered to the upper end of the cylinder in any suitable manner. This will swing crank 35 in a counter-clockwise direction and cause its free outer end to move the valve stem to valve closing position.

To cushion the impact of crank 35 against the valve stem, a socket member 41 is screwed on the outer end of yoke 28. The outer end of this member is provided with an axial opening in which a plunger 42 is slidably mounted. Inside of the socket the plunger has a collar 43 which normally is pressed against the outer end of the socket by means of a coil spring 44 compressed

against the collar and the yoke. When, as shown in Fig. 2, crank 35 is swung toward the valve stem, it strikes the projecting end of this plunger which can slide into the socket against the resistance of the spring therein and thereby cushion the impact. As long as the crank is held in valve-closing position, the fluid pressure on diaphragm 19 has no effect on the valve. When the crank is swung in the opposite direction the compressed coil spring 31 on the control rod immediately slides block 22 up the rod to jam nuts 30 and thereby swings bell crank 24 counter-clockwise to fully open the valve, because the diaphragm already is in position to hold the valve wide open. This brings the speed of the turbine up quickly to its operating range.

According to the provisions of the patent statutes, I have explained the principle of my invention and have illustrated and described what I now consider to represent its best embodiment. However, I desire to have it understood that, within the scope of the appended claim, the invention may be practiced otherwise than as specifically illustrated and described.

I claim:

Speed regulating apparatus comprising a valve housing, a valve member in the housing for controlling fluid flow through it, an axially movable stem connected to the valve member for moving it and projecting from the housing, a control stem mounted adjacent the outer end of the valve stem at an angle thereto, means operatively connected to the control stem for moving it axially, a crank pivotally mounted beside the adjacent ends of the two stems, means operatively connecting one end of the crank to the valve stem for movement therewith in opposite directions, the opposite end of the crank being movable lengthwise of the control stem, means on the control stem limiting movement of said opposite end of the crank along the control stem in such direction that movement of the control stem in the opposite direction will close the valve, and a spring on the control stem resisting movement of the crank away from said limiting means so that movement of the control stem in the direction opposite to its valve-closing direction normally will open the valve, and selectively operable means for moving the valve stem and crank against the resistance of the spring to close the valve independently of the control stem.

COARTLAND HOWLAND LANGWORTHY.
